CATALOGUE ORDER CARD BINDER

William Neer, Waukegan, Ill., assignor to Jewell Tea Co. Inc., Melrose Park, Ill., a corporation of New York

Application June 15, 1956, Serial No. 591,727

3 Claims. (Cl. 129—1)

This invention relates generally to inventory catalogues and order cards and more particularly relates to improved methods and means for positioning and retaining looseleaf sheets or cards in side-by-side alignment and recording statistical information thereon.

Although the principles of the present invention are of general utility, a particularly useful application is found in connection with the maintenance of a running inventory record such as is required in the operation of a large volume food market. There is provided a binder device providing a flat support surface for a plurality of looseleaf catalogue sheets bearing inventory information with respect to the stock on hand. A plurality of order cards of the type adapted to have marked thereon electrically conductive indicia markings for use in automatic tabulator machines are arranged in side-by-side relation to the looseleaf sheets. The cards and the looseleaf sheets are retained at one longitudinally extending edge by a ring binder, thereby facilitating use of both sides of the sheets or cards and the body member is particularly characterized by the provision of at least a pair of pins projecting upwardly from the support surface in laterally spaced relation to the ring binder. The projecting pins are also spaced apart from one another longitudinally and are positioned to retain and align adjoining laterally extending edges of the adjacent sheets or cards in relatively fixed position on the surface.

It is further contemplated, according to the principles of the present invention, to equip the binder device with a pivotal handle on the back surface thereof to facilitate use of the device by either right-handed or left-handed operators.

It is an object of the present invention, therefore, to provide a binder device which effects accurate alignment between a catalogue sheet and an order card, even though retained within the device by a looseleaf-type ring binder.

It is another object of the present invention to provide a device for binding catalogue sheets and order cards and for retaining the sheets and cards in aligned position without obscuring or interfering with the full effective use of the indicia surfaces on the sheets and cards.

Another object of the present invention is to provide a looseleaf binder having additional alignment and retainer means which will maintain the insert pages in alignment even though the ring binder apertures in the pages are torn.

Another object of the present invention is to provide a ring binder device for catalogue sheets and order cards which is rugged in construction and simple in operation.

Yet another object of the present invention is to provide a catalogue order card binder which facilitates use of both sides of the catalogue sheets and order cards, but

2

which will lock the sheets and cards in aligned side-by-side relation in use.

A further object of the present invention is to provide a binder with a pivoted handle which will facilitate use thereof by right-handed or left-handed operators.

Many other advantages, features and additional objects of the present invention will become manifest to those versed in the art upon making reference to the detailed description which follows and the accompanying sheet of drawings in which a preferred structural embodiment of a catalogue order card binder embodying the principles of the present invention is shown by way of illustrative example.

Figure 1 is a broken elevational view of a catalogue order card binder provided in accordance with the principles of the present invention;

Figure 2 is a side broken elevational view of the binder device of Figure 1; and

Figure 3 is a greatly reduced rear elevational view of the binder device shown in Figures 1 and 2.

As shown on the drawings:

The binder device of the present invention is indicated generally by the reference character A and includes a longitudinally extending backbone portion B having projecting laterally therefrom a first body portion C having a support surface D on one face thereof and a second body portion E formed with a support surface F on one face thereof.

On a back surface G formed on the body portion C, an elongate handle H is provided. The handle H is formed with an offset lug I suitably apertured to receive a pivot pin such as may be provided by a rivet J, thereby swingably mounting the handle H for movement relative to the body portion C. A support lug K is offset from the opposite end of the handle H and has an enlarged bearing surface for engaging up against the back surface G on the body portion C in whatever position of adjustment is desired by the user of the binding device A. In Figure 3, for example, the handle H is shown in full line and in dotted line position, the two positions being representative of alternative positions likely to be selected by a right-handed user and a left-handed user.

A longitudinally extending ring binder L having a plurality of rings indicated at M is assembled on the backbone portion B between the oppositely extending support surfaces D and F, and is retained thereon in firm assembly by a plurality of fasteners such as the screws N. For convenience in the further description of the invention, the rings are indicated at M1, M2 and M3.

There is provided in accordance with the principles of the present invention, a catalogue sheet O which has a longitudinally extending marginal edge P formed with a pair of spaced apertures Q and R. The apertures Q and R engage the rings M1 and M2, respectively. The indicia bearing surface of the catalogue sheet O extends laterally from the ring binder L and spreads over the support surface F on the body portion E, or if turned on its opposite side, spreads over the support surface D of the body portion C.

The catalogue sheet O illustrated constitutes a typical catalogue sheet as is used in food store practice. Thus, the first column S indicates the item number and the second column T indicates the number of goods in the shipping package more particularly described in the "description" column indicated at U. The size of the package in which the goods are provided is indicated in the

column V and the selling price is shown in the column W. Four subdivided columns are provided to indicate the inventory on hand in column X and the amount to be ordered in the column Y. Line numbers are designated in the column Z.

An order card is shown at AA. The order card AA is of the type utilized for converting recorded information into electrical signals and in the particular form illustrated has a plurality of indicators BB which can be marked with a marking pencil of the type adapted to apply to the selected designator BB an electrically conductive indicia which will cooperate with suitable mechanism of automatic business machines.

Thus, there is a first column on the order card AA which indicates line numbers, the column being shown at CC and the face of the card is divided into three columns DD, EE and FF to afford various number combinations over a selected range. For example, to indicate any number between 1 and 10, an appropriate designator BB in the column DD or EE is marked. To indicate a number between 10 and 20, the designator under 10 in column FF is marked together with an appropriate designator BB in the columns DD and EE.

The catalogue sheet O is provided with a page number as at GG and a corresponding indication can be made on the order card AA at a horizontally extending row of indicia indicated at HH.

Because food market inventories vary widely as to the type of stock in different stores and also as to the stock on hand for different seasons of the year, it is highly desirable that looseleaf catalogue sheets be provided to afford the necessary flexibility required. For efficient use of the order cards AA, however, there must be perfect alignment between the catalogue sheet O and the order card AA. Any ordinary looseleaf binding is characterized by so much relative misalignment as to make the effective use of the order cards impractical. Permanent bindings, of course, are far too expensive and perforated tear cards are undesirable since replacement of the order cards would require reprinting of all of the catalogue sheets.

In accordance with the principles of the present invention, the support surfaces D and F are characterized by the provision thereon of at least a pair of pins projecting upwardly in laterally spaced relation to the ring binder L and spaced apart from one another longitudinally to retain and align adjoining laterally extending edges of the adjacent sheet O and card AA on the corresponding support surface.

Thus, the catalogue sheet O has a laterally extending edge II which is positioned directly adjacent the laterally extending edge JJ of the order card AA. Adjacent the edge II and spaced laterally from the longitudinal edge P of the order sheet O, there is a locating pin KK carried by the body portion E and projecting upwardly from the support surface F into engagement with a corresponding aperture LL formed in the catalogue sheet O. The aperture LL is formed in the corner bounded by the lateral edge II and the outermost longitudinal edge MM of the catalogue sheet O and, accordingly, does not obscure any of the indicia markings on the catalogue sheet O.

A second locating pin NN is carried on the body portion E and projects upwardly from the support surface F for engagement with an aperture OO formed in the order card AA. The aperture OO is formed adjacent the lateral edge JJ of the order card AA and also adjacent a longitudinal edge PP on the outermost portion of the card AA.

The inner longitudinal edge QQ of the order card AA has an aperture RR formed therein for cooperation with the ring M3 of the ring binder L.

Because of the size of the catalogue sheet O and because the quality of the paper stock employed in some catalogue sheets, it may be desirable to provide an addi-

tional locating pin SS on the body portion EE projecting upwardly from the support surface F and received in an aperture TT formed in the catalogue sheet O adjacent the longitudinal edge MM. The pin SS is spaced longitudinally from the pin KK.

It will be understood that the body portion C is provided with corresponding locating pins. Similar reference characters have been applied for the sake of convenience. It will be noted that the aperture OO formed in the order card AA is in the extreme corner position, thereby providing the alignment feature without obscuring or interfering with the sensing marks affixed on the designators BB. The alignment pins SS, KK and NN hold the sheet and card members in alignment even though the ring binder apertures Q, R and RR may be enlarged or if the edge portions thereof are torn.

If desired, the binder device A may be provided with an extension portion UU having a clip VV for carrying a marking pencil WW of the type including a marking compound XX adapted to provide sensing indicia marks on the designators BB of the order card AA.

Although various minor modifications might be suggested by those versed in the art, it should be understood that I wish to embody within the scope of the patent warranted hereon all such modifications as reasonably and properly come within the scope of my contribution to the art.

I claim as my invention:

1. A catalogue binder device comprising a body member providing a flat support surface, a plurality of matched pairs of looseleaf sheets or cards arranged in side-by-side relation on said surface, a longitudinally extending ring binder on said body member common to both of each said pair of sheets or cards and binding one longitudinal edge of the matched pairs of sheets or cards, and at least one pair of pins carried by said body member and projecting perpendicularly upwardly from said surface in laterally spaced relation to said ring binder and spaced apart from one another longitudinally, each said sheet or card having an aperture for snugly receiving a corresponding pin to retain and align adjoining laterally extending edges of adjacent sheets or cards on said surface.

2. A catalogue device comprising a body member providing a generally rectangular support surface, a longitudinally extending ring binder on said body member dividing said surface into first and second support surfaces on said body member extending laterally from opposite sides of said ring binder, a plurality of matched pairs of looseleaf sheets or cards attached to said ring binder and having laterally extending inner edges disposed across said surfaces adjacent one another, and a pair of pins for each of said first and second surfaces carried by said body member and projecting upwardly from each of said first and second surfaces perpendicular to said ring binder and in laterally spaced relation to said ring binder, each of said pins being spaced longitudinally with respect to one another, each matched pair of looseleaf sheets or cards having a corresponding pair of apertures formed therein snugly receiving said pins to retain and align said adjoining laterally extending edges of adjacent sheets or cards on said surface, one pair of said pins holding the sheets or cards for use on one side thereof when positioned on said first support surface and the other pair of pins holding the same sheets or cards for use on the opposite side thereof when positioned on said second support surface.

3. A catalogue binder device comprising a body member providing a flat support surface, a plurality of matched pairs of looseleaf sheets or cards arranged in side-by-side relation on said surface, a longitudinally extending binding means on said body member common to both of each said pair of sheets or cards and binding one longitudinal edge of the matched pairs of sheets or cards, and at least one pair of pins carried by said body member and projecting perpendicularly upwardly from

said surface in laterally spaced relation to said binding means and spaced apart from one another longitudinally, each said sheet or card having an aperture for snugly receiving a corresponding pin to retain and align adjoining laterally extending edges of adjacent sheets or cards 5

CERTIFICATE OF CORRECTION

Patent No. 2,878,813

March 24, 1959

William Neer

It is hereby certified that error appears in the above numbered patent requiring correction and that the said Letters Patent should read as corrected below.

In the grant, lines 2 and 12, and in the heading to the printed specification, lines 3 and 4, name of assignee, for "Jewell Tea Co. Inc.," each occurrence, read -- Jewel Tea Co. Inc., --.

Signed and sealed this 25th day of August 1959.
